UNITED STATES PATENT OFFICE.

MICHAEL KUNIK, OF CHICAGO, ILLINOIS.

MICROMETER-CALIPERS.

1,070,816.

Specification of Letters Patent. Patented Aug. 19, 1913.

Application filed March 4, 1912. Serial No. 631,436.

To all whom it may concern:

Be it known that I, MICHAEL KUNIK, a citizen of the United States, and a resident of the city of Chicago, county of Cook, and State of Illinois, have invented certain new and useful Improvements in Micrometer-Calipers, of which the following is a specification.

My invention relates to improvements in calipers and more specifically to that class thereof characterized because of the adaptability thereof for micrometric adjustment.

The object of my invention is the production of a caliper of the character mentioned which may be readily and quickly adjusted to nearly the proper dimensions and then as easily and expeditiously adjusted to the exact measurement.

A further object is the production of a caliper as mentioned which will be of durable and economical construction and efficient in use.

Other objects will appear hereinafter.

The invention consists in the combinations and arrangements of parts hereinafter described and claimed.

My invention will be best understood by reference to the accompanying drawing forming a part of this specification, and in which,

Figure 1 is a side elevation of a micrometer caliper embodying my invention, Fig. 2 is a vertical central longitudinal section thereof, portions however being shown in elevation, Fig. 3 is a slightly enlarged detail section taken on line 3-3 of Fig. 1, and Fig. 4 is a sectional detail of the outer end portion of the caliper stock.

The preferred form of my construction as illustrated in the drawing comprises a tubular stock consisting of the tubular portions 1 and 2, the adjacent ends of the members 1 and 2 being telescoped and preferably secured rigidly together by shrinking. Secured rigidly upon one end of the stock or upon the outer end of the member 1 is the fixed jaw 3 which is of the ordinary design.

Surrounding the outer end portion of the member 2 is a sleeve 4 which is tightly fitted thereon, the same being held in position by friction. Provided upon one side of the outer surface of the sleeve 4 is a series of graduations 5, divided according to any standard desired, as inches, the numbered graduations being tenths of inches

and the smaller divisions fortieths. Provided at one end of the sleeve 4 is a perforation 6 which affords means for engagement by a circular wrench for effecting rotary adjustment of said sleeve in order to properly position the longitudinal graduation with respect to graduations on the barrel as will be presently described. The barrel just referred to is shown at 7, the same being slidably and rotatably mounted upon the sleeve 4. One end of said barrel is circumferentially graduated, the graduations 8 being arranged for cooperation with the longitudinal graduation upon said sleeve 4, the adjacent terminal edge of said barrel 70 coöoperating with the transverse graduations 5 in the manner well known. The circumference of barrel 7 may be divided into any number of sections, that is the graduations 8 may be any desired distance apart, 75 said circumference being however divided preferably into twenty-five sections in order that measurements in the thousandths of an inch may be made as set forth hereinafter. The opposite end of the barrel 7 is preferably knurled as shown in order to facilitate rotation thereof by the fingers. Said end of said barrel is provided internally with a tapering seat 9 for the reception of the correspondingly formed end 10 of a screw 11 85 arranged co-axial with said barrel. The screw 11 engages the adjacent end portion of the stock member 2 which is internally screw threaded to receive the same, the outer end of said screw being provided with a 90 cylindrical extension 12 which slidably engages the opening through the members 1 and 2 in order to maintain said screw in proper axial position in the stock. The internally threaded end of the member 2 is 95 also split longitudinally and the outer surface thereof is tapering in form and screw threaded. Threaded upon said tapered portion is a collar 13 through the medium of which said end of said block member 2 may 100 be contracted in order to take up wear upon the internal thread of said block member or upon the threads of the screw 11. Said screw 11 is securely locked to the barrel 7 through the medium of the threaded connection 14 and the cap 15 so that rotation of said barrel will effect corresponding movement of said screw and hence longitudinal feeding of said barrel. By reason 105 of the peculiar connection between the 110

2
screw 11 and said barrel a construction is afforded which permits of relative adjustment of said parts, it being clear that by simply relaxing the connection 14 said barrel will be released and permit of rotary adjustment thereof relative to said screw. Also, this connection is such that the proper co-axial relation of said screw and barrel will always be maintained, since seating of the end 10 of said screw into the seat 9 in said barrel necessitates the proper relative positions of the axes of said parts. The head or enlarged portion of the connection 14 is provided with a transversely extending opening 16 for the reception of a pointed tool or pin for effecting rotation thereof.

Arranged upon the outer end of the connection 14 is a yoke 17 arranged parallel to the jaw 3. Secured in the outer end of said yoke is a tube 18 which is disposed parallel with the caliper stock. The yoke 17 is secured to the connection 14 through the medium of nuts 19 and the washer 20; said nuts also serving as a means of locking the calipers in positions of adjustment it being clear that by tightening said nuts the head of connection 14 will be drawn against the adjacent side of the yoke 17 to lock the same and hence the barrel against rotation.

Secured in the fixed jaw 3 of the calipers is a cylindrical bar 21 which engages and telescopes with the tube 18 as clearly shown, said bar serving to maintain said tube and hence the yoke 17 in proper sliding relation with said fixed jaw 3. Mounted upon the tube 18 for slidable adjustment thereon is the relatively movable jaw 22. Said jaw 22 is locked in its positions of adjustment through the medium of a set screw 23 the inner pointed end of said screw being adapted to engage correspondingly formed recesses 24 provided for engagement thereof in the side of the tube 18. It will be observed that the recesses 24 are arranged in pairs, the right hand recesses of said pairs being provided for engagement by the set screw 23 for securing the jaw 22 in position for outside caliper, the left hand recesses of said pairs being positioned for engagement by said screw in securing said jaw for inside caliper, the distance between the recesses in each pair being identical with the combined thickness of the points 25 of the caliper jaws. To illustrate this point it might be stated that the movable jaw as shown in Fig. 1 is arranged for outside caliper, the distance between the adjacent surfaces of the points 25 being indicated upon the scale below in the usual manner. If it is desired to use the calipers for inside measuring the screw 23 will be relaxed and the jaw 22 moved toward the jaw 3 and said screw engaged with the left hand recess, in which position the outside or remote surfaces of said points 25 will be separated the

distance shown at the graduations below or the same distance as were the inner surfaces of said points when the movable jaw was in its first position. By providing a number of pairs of recesses 24 spaced apart at known distances as one inch, when it is desired to make a measurement, the movable jaw may first be adjusted according to said recesses to roughly or nearly correspond with the measurement which is to be taken, the minuter adjustment being effected by rotation of the barrel 7. In this latter regard it may be stated that the pitch of the threads of screw 11 is preferably such that by turning the barrel 7 through one complete revolution the same will be moved longitudinally a distance corresponding with one of the smaller divisions of the scale 5 or one-fortieth of an inch, the provision of twenty threads to the inch upon said screw effecting this result. With this provision and with the provision of twenty-five graduations or divisions around the circumference of barrel 7 as above mentioned the rotation of said barrel through one of the divisions thereof will move said barrel and hence the jaw 22 through one-thousandths of an inch. Thus an instrument is provided whereby minute adjustments are readily and easily afforded, the adjustment to one-thousandths of an inch being made with great accuracy and because of the relatively coarse graduations upon the barrel, with ease and expedition.

A caliper of the construction as set forth is durable and economical, the same may be readily manipulated and is of high efficiency in use.

While I have illustrated and described the preferred form of construction for carrying my invention into effect, this is capable of variation and modification without departing from the spirit of the invention. I therefore do not wish to be limited to the precise details of construction as set forth, but desire to avail myself of such variations and modifications as come within the scope of the appended claims.

Having described my invention what I claim as now and desire to secure by Letters Patent is:

1. In a caliper, the combination of two jaws adapted to measure inside and outside dimensions; a screw arranged to feed said jaws toward and away from each other, one of said jaws being adjustably mounted with respect to said screw; graduations for measuring the feed of said jaws; means for accurately positioning said adjustable jaw in two different positions with respect to said screw, whereby said graduations will read for both the inside and outside measurements of said jaws, said means comprising a set screw carried by said adjustable jaw and provided with a conical inner end and

recesses in its mounting member adapted to receive said inner end snugly, substantially as described.

2. In a caliper, the combination of two jaws adapted to measure inside and outside dimensions; a screw arranged to feed said jaws toward and away from each other, one of said jaws being adjustably mounted with respect to said screw; graduations for measuring the feed of said jaws; and a plurality of sets of means for accurately positioning said adjustable jaws in two different positions with respect to said screw, whereby said graduations will read for both inside and outside dimensions of said jaws, substantially as described.

3. In a caliper, the combination of two jaws adapted to measure inside and outside dimensions; a screw arranged to feed said jaws toward and away from each other, one of said jaws being adjustably mounted with respect to said screw; graduations for measuring the feed of said jaws; a plurality of sets of means for accurately positioning said adjustable jaws in two different positions with respect to said screw, whereby said graduations will read for both inside and outside dimensions of said jaws, said means comprising a set screw carried by said adjustable jaw and provided with a conical inner end and a plurality of pairs of recesses in its mounting member adapted to receive said inner end snugly, substantially as described.

4. In a caliper, the combination of a 35 tubular stock; a fixed jaw carried by one end of said stock, said stock being provided with an internal screw thread; a circumferentially graduated barrel slidably and rotatably mounted upon said stock; a screw 40 connected with said barrel and engaging said internal screw thread of said stock; a tube extending parallel with said stock and said barrel and connected for movement with the latter; a bar fixed at one end to 45 said fixed jaw and having its free end telescoping said tube; a jaw mounted for slideable adjustment on said tube; and a set screw for securing said jaw in positions of adjustment, there being recesses in one side 50 of said tube for engagement by said set screw, said recesses being arranged in pairs, one recess of each of said pairs being adapted for engagement by said set screw to position said movable jaw relatively to said 55 graduations for inside caliper, and the other of said recesses being adapted for arrangement of said set screw to position said movable jaw relatively by said graduations for outside caliper, substantially as described.

In testimony whereof I have signed my name to this specification in the presence of two subscribing witnesses.

MICHAEL KUNIK.
